(57) CLAIM

The ornamental design for a sliding webcam cover, as shown and described.

DESCRIPTION

FIG. 1 is a front, top, and right perspective view of the first embodiment of a sliding webcam cover in an open configuration to expose a webcam of an electronic device;

FIG. 2 is a front, top, and right perspective view thereof in a closed configuration to cover a webcam of an electronic device;

FIG. 3 is a front elevational view thereof in an open configuration;

FIG. 4 is a top plan view thereof;

FIG. 5 is a bottom plan view thereof;

FIG. 6 is a left elevational view thereof;

FIG. 7 is a right elevational view thereof;

FIG. 8 is a rear elevational view thereof;

FIG. 9 is a front elevational view thereof in a closed configuration;

FIG. 10 is a top plan view thereof;

FIG. 11 is a bottom plan view thereof;

FIG. 12 is a front, top and right perspective view of the second embodiment of a sliding webcam cover in an open configuration to expose a webcam of an electronic device;

FIG. 13 is a front, top, and right perspective view thereof in a closed configuration to cover a webcam of an electronic device;

FIG. 14 is a front elevational view thereof in an open configuration;

FIG. 15 is a top plan view thereof;

FIG. 16 is a bottom plan view thereof;

FIG. 17 is a left elevational view thereof;

FIG. 18 is a right elevational view thereof;

FIG. 19 is a rear elevational view thereof;

FIG. 20 is a front elevational view thereof in a closed configuration;

FIG. 21 is a top plan view thereof;

FIG. 22 is a bottom plan view thereof;

FIG. 23 is a front, top and right perspective view of the third embodiment of a sliding webcam cover in an open configuration to expose a webcam of an electronic device;

FIG. 24 is a front, top, and right perspective view thereof in a closed configuration to cover a webcam of an electronic device;

FIG. 25 is a front elevational view thereof in an open configuration;

FIG. 26 is a top plan view thereof;

FIG. 27 is a bottom plan view thereof;

FIG. 28 is a left elevational view thereof;
FIG. 29 is a right elevational view thereof;
FIG. 30 is a rear elevational view thereof;
FIG. 31 is a front elevational view thereof in a closed configuration;
FIG. 32 is a top plan view thereof; and,
FIG. 33 is a bottom plan view thereof.

The broken lines shown in the drawings depict environmental subject matter (specifically an electronic device in FIGS. 1, 2, 12, 13, 23 and 24) and portions of the sliding webcam cover that form no part of the claimed design.
